UNITED STATES PATENT OFFICE

147,841

DESIGN FOR A SERVICE MOTOR TRUCK

Kibbey W. Couse, Newark, N. J.

Application May 28, 1946, Serial No. 130,170

Term of patent 7 years

(Cl. D14—3)

To all whom it may concern:

Be it known that I, Kibbey W. Couse, a citizen of the United States and a resident of Newark, in the county of Essex and State of New Jersey, have invented a new, original, and ornamental Design for a Service Motor Truck, of which the following is a specification, reference being had to the accompanying drawings, forming part thereof.

Fig. 1 is an elevational view of one side of a service motor truck showing my new design;

Fig. 2 is a similar view showing the covers of the truck elevated;

Fig. 3 is a front elevational view of the service motor truck as it is illustrated in Fig. 1;

Fig. 4 is a front elevational view of the service motor truck as it is illustrated in Fig. 2;

Fig. 5 is a rear elevational view of the service motor truck as it is illustrated in Fig. 1; and

Fig. 6 is a similar view of the service motor truck with the covers elevated as shown in Fig. 2.

The other side of the truck is substantially the same as that shown.

I claim:

The ornamental design for a service motor truck, as shown and described.

KIBBEY W. COUSE.
